Patented Dec. 30, 1975

238,295

LAMP SHADE

Kenneth Yuhung Tongson, Kowloon, Hong Kong, assignor to Star Industrial Company, Limited, Kowloon, Hong Kong

Filed Apr. 26, 1974, Ser. No. 464,659

Claims priority, application Great Britain Oct. 29, 1973

Term of patent 7 years

Int. Cl. D26—05

U.S. Cl. D48—16 D

FIG. 1

FIG. 2

FIG. 4

FIG. 1 is a front perspective view of a lamp shade showing my new design, the rear being similar;

FIG. 2 is a bottom plan view thereof;

FIG. 3 is a vertical cross-sectional view thereof;

FIG. 4 is a horizontal cross-sectional view thereof.

I claim:

The ornamental design for a lamp shade, substantially as shown and described.
